UNITED STATES PATENT OFFICE.

CHARLES L. METZGER, JOSEPH A. FORSTER, AND WILLIAM E. KUNE, OF OAKLAND,
CALIFORNIA.

SOUND-OPERATING MECHANISM.

1,101,497.

Specification of Letters Patent. Patented June 23, 1914.

Application filed July 22, 1913. Serial No. 720,608.

To all whom it may concern:

Be it known that we, CHARLES L. METZGER, JOSEPH A. FORSTER, and WILLIAM E. KUNE, citizens of the United States, residing at 5 Oakland, in the county of Alameda and State of California, have invented certain new and useful Improvements in Sound-Operating Mechanisms, of which the following is a specification.

10 This invention relates to sound producing devices, for the imitation of natural sounds in connection with moving pictures or stage effects.

The principal object of our invention is 15 to produce a simple and effective device for imitating the effect of engine exhaust, which device formed a part of the application under Ser. #704,379.

Another object of our invention is to provide improved means for throwing the sound producing devices into operation from a distant point so that the device may be operated by the camera operator, or from the musical instrument.

25 With the above and other objects in view as will hereinafter be described, our invention comprises certain new and novel combinations and arrangements of parts as will be fully described in the following specifications and more particularly pointed out in 30 the appended claims.

In the accompanying drawings like characters of reference denote like parts in the several views, and:—Figure 1 is a view in 35 elevation of our improved device showing a diagrammatic view of the control circuit used therewith. Fig. 2 is a view in section on the line 2—2 Fig. 1. Fig. 3 is a view in section on line 3—3 Fig. 1.

40 On a suitable base 1 are mounted standards 2 which serve to support a shaft 3, having thereon a belt pulley 4. The latter is constantly driven by a belt 5 from the belt pulley 6 on other motor 7, or other source 45 of power.

On the shaft 3 is a sleeve 8 from which extend the arms 9 to which are connected magnet coils 10. Adjacent this collar there is provided a collar 11, which is insulated 50 from the shaft 3 and adjacent parts by insulation 12. On the adjoining standard 2 there is a block of insulating material 13, whereon is mounted a contact brush 14, adapted to contact with collar 11. Binding 55 parts 15, 16 and 17 are provided respectively

on sleeve 8, collar 11 and brush 14. One end of the magnet coils is connected by a conductor wire 18 to the binding part 15 and thus grounded, the other end is connected with a conductor wire 19 with the binding 60 part 16 and from 17 extends a conductor wire 20 which is connected with a battery or other source of electric power 21. From the other side of this battery a wire 22 leads to a binding part 23 where it is grounded 65 on the frame. A suitable key 24 is placed in the circuit to control the operation and this key may be located at any convenient point.

Slidably mounted on the shaft 3 is a sleeve 70 25 having at the end adjacent the magnets a disk 26 which forms an armature for the said magnets. Between the disk 26 and the magnets is interposed a leaf spring 27, which normally holds the disk away from 75 the magnet. Fixed on the sleeve 25 is a hub 28 having a plurality of radial arms 29, which vary in number according to the speed of exhaust which it is desired to imitate. Thus while we have shown two arms 80 there may, on the same shaft, be mounted other magnets and disks having 3, 4 or more arms so that by successively throwing into operation the speed of exhaust will be 85 gradually increased.

On the face of each arm is fastened a strip 90 30, of rough material such as sand-paper, and this strip when the device is in operation contacts successively with a series of pin like points 31 mounted in a block 32. 95 The latter is mounted on a bracket 33, which is attached to the base 1.

In the operation of this device when the key 24 is closed the magnets 10 will be energized attracting the disk 26 against the cores thereof, and cause to revolve therewith, at the same time the sand-paper is pulled forward into contact with points 31 and produces a sound which imitates the exhaust of 100 an engine.

While we have shown the preferred embodiment of our invention it will be understood that modifications in form and detail of construction may be resorted to without departing from the spirit thereof.

What we claim and wish to cover by Letters Patent, is:—

1. In an apparatus of the class described, a device for imitating the exhaust of a locomotive comprising a shaft, means to drive 110

- said shaft, a hub slidably and rotatably mounted on said shaft, friction producing means carried by said hub, coacting means adjacent the path of said friction producing means and adapted to engage the friction producing means when the hub is slid along the shaft and rotated, and means to simultaneously move said hub along the shaft and cause the hub to rotate with the shaft.
- 5 2. In an apparatus of the class described, a device for imitating the exhaust of a locomotive, comprising a shaft, means to drive said shaft, a hub slidably and rotatably mounted on said shaft, arms extending from said hub, sand-paper strips carried by said arms, a supporting bracket adjacent the path of said arms, a block secured to said supporting bracket, and a multiplicity of pin teeth extending through said block and 10 normally spaced from the path of said sand-paper, and means to simultaneously rotate said hub and move the same to bring the sand-paper into contact with the pins during rotation.
- 15 3. In a device of the class described, a device for imitating the exhaust of a locomotive comprising a shaft, means to drive said shaft, a hub slidably and rotatably mounted on said shaft, arms extending from said hub, sand-paper strips carried by said arms, a supporting bracket adjacent the path of said arms, a block secured to said supporting bracket, and a multiplicity of pin teeth extending through said block and 20 normally spaced from the path of said sand-paper, and means to simultaneously rotate said hub and move the same to bring the sand-paper into contact with the pins during rotation.
- 25
4. In an apparatus of the class described, a device for imitating the exhaust of a locomotive comprising a shaft, means to drive said shaft, a hub slidably and rotatably mounted on said shaft, coacting means adjacent the path of said friction producing means and adapted to engage the friction producing means when the shaft is slid along the hub, magnets carried by said shaft, a collar carried by said shaft and insulated therefrom, one end of the magnet winding being connected to the collar and the other end being grounded, a fixed contact engaging said collar and adapted for connection to a source of electricity, and a disk connected to said hub and constituting an armature for said magnets.
- 45
5. In an apparatus of the class described, a device for imitating the exhaust of a locomotive comprising a shaft, means to drive said shaft, a hub slidably and rotatably mounted on said shaft, coacting means adjacent the path of said friction producing means and adapted to engage the friction producing means when the shaft is slid along the hub, magnets carried by said shaft, a collar carried by said shaft and insulated therefrom, one end of the magnet winding being connected to the collar and the other end being grounded, a fixed contact engaging said collar and adapted for connection to a source of electricity, and a disk connected to said hub and constituting an armature for said magnets.
- 50
6. In an apparatus of the class described, a device for imitating the exhaust of a locomotive comprising a shaft, means to drive said shaft, a hub slidably and rotatably mounted on said shaft, coacting means adjacent the path of said friction producing means and adapted to engage the friction producing means when the shaft is slid along the hub, magnets carried by said shaft, a collar carried by said shaft and insulated therefrom, one end of the magnet winding being connected to the collar and the other end being grounded, a fixed contact engaging said collar and adapted for connection to a source of electricity, and a disk connected to said hub and constituting an armature for said magnets.
- 55
7. In an apparatus of the class described, a device for imitating the exhaust of a locomotive comprising a shaft, means to drive said shaft, a hub slidably and rotatably mounted on said shaft, coacting means adjacent the path of said friction producing means and adapted to engage the friction producing means when the shaft is slid along the hub, magnets carried by said shaft, a collar carried by said shaft and insulated therefrom, one end of the magnet winding being connected to the collar and the other end being grounded, a fixed contact engaging said collar and adapted for connection to a source of electricity, and a disk connected to said hub and constituting an armature for said magnets.
